UNITED STATES PATENT OFFICE.

LEONARD H. HERSKOVITZ, OF NEW YORK, N. Y.

DESIGN FOR A SMOKER'S SET.

Application filed June 30, 1926. Serial No. 18,215. Term of patent 7 years.

To all whom it may concern:

Be it known that I, LEONARD H. HERSKOVITZ, a citizen of the United States, and resident of the borough of Manhattan, in the city and State of New York, have invented a new, original, and ornamental Design for a Smoker's Set, of which the following is a specification, reference being had to the accompanying drawing, forming a part thereof.

The drawing represents a perspective view of a smoker's set, showing my new design.

I claim:

The ornamental design for a smoker's set substantially as shown.

LEONARD H. HERSKOVITZ.
